Primary Examiner — Keli L Hill(74) *Attorney, Agent, or Firm* — Grant's Law firm; Allan Howard Grant(57) **CLAIM**

I claim the ornamental design for a puck rub, as shown and as described.

DESCRIPTION

FIG. 1 is a top perspective view of the puck rub.

FIG. 2 is a bottom perspective view of the puck rub.

FIG. 3 is a side view of the puck rub.

FIG. 4 is a top view of the puck rub.

FIG. 5 is bottom view of the puck rub; and,

FIG. 6 is a perspective of the puck rub showing a User removing the dipping tobacco from the User's finger.

The broken lines shown are included for the purpose of illustrating portions of the puck rub that form no part of the claim.
